UNITED STATES PATENT OFFICE.

FRANK W. HOWARD, OF NEW YORK, N. Y.

RAINCOAT.

1,358,852.

Specification of Letters Patent. Patented Nov. 16, 1920.

Application filed December 26, 1916. Serial No. 139,000.

To all whom it may concern:

Be it known that I, FRANK W. HOWARD, a citizen of the United States, and a resident of the city of New York, in the county of New York and State of New York, have invented certain new and useful Improvements in Raincoats, of which the following is a specification.

This invention relates to water proof 10 cloaks or raincoats of a simple type, capable of being manufactured and sold for a nominal charge, with the idea that these raincoats can be manufactured and placed on sale at many points throughout each city, 15 where they would then be available for persons who have been unexpectedly caught in the rain. In order to accomplish this general purpose it is necessary to construct the raincoat of an inexpensive material. The 20 material I employ is water proof paper which is inexpensive but also more or less frangible and weak as compared with cloth. The general object of my invention is to produce a raincoat which is very simple and 25 inexpensive; and further to produce a raincoat which has a construction, particularly adapted to the frangible nature of the material, that is to say the construction of the raincoat is such as to eliminate unnecessary 30 seams and avoid the necessity for sleeves. To this end the raincoat is of simple form, so far as possible devoid of seams, and preferably of sleeveless form.

In its construction the raincoat comprises 35 a cape and a skirt so formed that arm holes are produced between the skirt and the cape through which one's arms are to be passed in putting on the raincoat. One of my objects is to provide such a coat with improved 40 means for supporting the forward portion of the skirt from the shoulders; also to insure that the cape will operate effectively to cover the arms. For this purpose I may employ connecting means extending upwardly from the skirt, and I provide for reinforcing such connecting means where necessary to insure that they will stand the strains, to which they may be subjected.

Further objects of the invention will appear hereinafter.

In the drawing which illustrates a preferred embodiment of my invention,

Figure 1 is a front elevation and partial section partly broken away, and showing a 55 raincoat embodying my invention;

Fig. 2 is a plan of a one-piece blank, also

of my invention from which the raincoat may be formed;

Fig. 3 is a vertical section taken about on the line 3—3 of Fig. 1 to illustrate the relation of the skirt and cape and the details of the connection between them; 60

Fig. 4 is a front elevation and partial section of a raincoat embodying my invention and illustrated as though constructed from 65 a built-up blank;

Fig. 5 is a plan partially broken away showing a built-up blank adapted to form the raincoat illustrated in Fig. 4; and

Fig. 6 is a detail horizontal section taken 70 on the line 6—6 of Fig. 2 to illustrate details of a reinforcement I may use.

Referring to Figs. 1 and 2 the raincoat comprises a skirt 1 and a cape 3, said cape having a neck opening 4 located between 75 shoulders 5. The space between the shoulders 5 and the upper side edges 6 of the skirt form the arm holes as at 6^a through which the arms are to be passed in putting on the raincoat. In other words, the upper 80 edge 6 of the skirt is located near the lower edge of the cape, and the edge 6 at each side cooperates with the cape to form an arm-hole. The upper middle portion of the skirt at the rear connects with the lower middle 85 portion of a rear apron 8^a forming the rear part of the cape 3, and the forward portion of the skirt 1 is in the form of two flaps which extend around to the front side of the 90 raincoat. In order to support the flaps 19 and 20 which form the forward portion of the skirt, I provide connecting means which 95 is preferably in the form of flaps 7 which extend up from the upper edge of the skirt, the upper ends of these flaps 7 being attached at an elevated point to the inner side of the forward apron 8 of the cape 3. These connecting means 7 perform a double function because they not only transmit the weight of the forward part of the skirt to 100 the shoulders 5, but they also operate beneficially because the weight of the skirt tends to hold down the forward apron on the breast. My object in attaching the flaps 7 at an elevated point on the apron 8 is to 105 provide a space behind the apron and in front of the flaps 7 which will receive the arms of the person wearing the coat and enable the cape to effectively cover the arms.

The extensions or flaps 7 are subjected to 110 considerable strain, particularly when the coat is worn in windy weather, and in order

to prevent their being torn, particularly at their vertical edges 9, I prefer to provide these vertical edges 9 with a reinforcing cord 10, and I produce a hem 11 in these edges 5 which envelops the cord.

A coat, such as that shown in Fig. 1, may be readily formed from a one-piece blank 12, such as that shown in Fig. 2. This blank comprises a cape portion 13 having a centrally disposed gap 14 intended to form the neck opening 4, and from this gap 14 diverging edges 15 extend outwardly, which edges are intended to form the meeting edges 16 of the cape. The cape portion 13 has side edges 17 which may be curved if desired as shown, and which extend up to meet the diverging edges 15. These edges 17 form the lower edge of the forward apron 8 of the cape in the finished raincoat.

Below the upper piece or cape portion 13, I provide a lower piece or skirt portion 18, which, in the present instance, is formed integral with the cape portion. This lower portion 18 has the flap 19 extending toward the right, and the similar flap 20 extending toward the left. In forming the raincoat these flaps extend around to the front, and in order to facilitate the shaping of the raincoat to the body I provide substantially 25 vertical plaits between creases 18^a which will come at the sides of the raincoat when completed, and facilitate its opening up to receive one's body.

In forming this blank from a sheet of 35 frangible material such as water proof paper I simply cut the material so as to form gaps 19^a and 20^a at each side, and adjacent to these gaps the upper edge of each of the flaps 19 and 20 is formed with 40 the extension or flap 7 referred to above.

Forming a raincoat from a one-piece blank expedites the formation of the complete coat. It is advisable to have the cape and skirt formed in one piece, in this way, 45 where it is possible to secure a sufficiently large piece of water proof paper, and also where it is not necessary for the forward apron of the cape to be of very great length. In this connection attention is called to the 50 fact that the peculiar shape of the blank necessarily imposes a limit upon the length of the cape at the front. This is evident from an inspection of Fig. 2, from which it will appear that the upper portion of the 55 flap 7 limits the length of the cape, that is to say, the outer edge of the cape portion 13 cannot extend beyond the inner upper corner of each of the flaps 7. For this reason,

if I wish to have a long cape at the front, 60 I prefer to produce the raincoat out of a blank which is built up of pieces instead of being made of one piece. A raincoat formed from such a blank is illustrated in Fig. 4. The built-up blank comprises a 65 substantially rectangular skirt portion or

skirt piece 22, the upper middle portion of which, adjacent the upper edge 23, is attached to the lower middle portion of the cape piece 24. This produces an overlapping circular segment 25 at the back of the 70 raincoat. I prefer that the edge 23 be attached only part of its length, for example, I attach it between the points 27 and 28. From the points 27 and 28, creases 29 are formed, extending vertically downward on 75 the skirt portion 22. And farther out beyond these creases 29 similar creases 30 are provided, producing plaits between them. These creases 29 and 30 have substantially the same function as the creases 18^a shown 80 in Fig. 2, but I am enabled to make these plaits wider in this case, because the points 27 and 28 can be located nearer the central vertical axis of the blank. Furthermore, it is evident that the points 27 and 28, as 85 located in Fig. 5 are within the curved edge 26, and this operates to virtually increase the projection of the edge 26 at the back of the corresponding gaps 27^a and 28^a, adjacent these points which are to form the arm-holes. In other words, the use of this built-up blank enables me to make the cape relatively longer and more effective as a covering for the arms.

It is evident that in this built-up blank, 95 the blank presents flaps 31 which extend in opposite directions from the middle of the blank like the flaps 19 and 20. The upper edges 22^a of these flaps 31 are provided with connecting flaps 32 formed of the same material, but made of separate pieces and secured along their lower edges 33 to the upper edges of the flaps 31. Obviously, if desired, the piece 24 may be made so large that its edge 26 will extend beyond and over 100 the flaps 32 when the blank is being formed. It is understood of course that in forming the blank no connection is made between the flaps 32 and the cape piece 24. This attachment is made only after the blank 110 is formed up into the raincoat. When this has been done, the upper edges of the flaps 32 are attached at an elevated point (see Fig. 4), to the inner side of the forward apron 35 of the cape 36.

The vertical edges 37 of the flaps 32 are preferably provided with cords 38 similar to the cords 10 described in connection with the one-piece blank.

In the one-piece blank I prefer to provide the entire edge of the blank with a hem 40 enveloping a continuous reinforcing cord 39.

And in constructing the built-up blank I prefer to provide each separate piece of the 125 blank with a similar reinforcing cord 39^a enveloped in a hem 40^a.

The edges may be either glued or sewed when turned over to form the hem. In both forms of the blank the parts are cut so that 130

the raincoat will be divided substantially vertically down the front and will have enough material to form an overlap of the forward edges 41, see Fig. 4; and in order 5 to secure these overlapping edges together, I prefer to provide buttons 42 riveted to the garment and carrying cords or ties 43, the ends of which may be passed several times around a fastener or button 44 at 10 tached to the opposite edge of the coat.

In the blank of the form shown in Fig. 5 it is evident that the diverging edges 45 of the blank of the cape-portion may be made as long as desired. When this line 45 is 15 made long the cape can be made to hang with a considerable dip along its front line as will be evident from an inspection of Fig. 4, and it can also be made sufficiently long in the vicinity of the gaps 27^a and 28^a 20 to insure that it will effectively cover the arm-holes at the back. Furthermore, on account of the greater length of the cape at the front it is evident that the garment as shown in Fig. 4 will give greater freedom of movement 25 to the arms under the cape, and will enable one to carry bundles in the arms and under the cape.

In the finished raincoat of the form illustrated in Fig. 4 it is evident that the cape 30 36 will form shoulders 36^a and will have a neck opening 36^b similar to the corresponding parts of the raincoat illustrated in Fig. 1.

It is understood that the embodiment of 35 the invention described herein is only one of the many embodiments this invention may take, and I do not wish to be limited in the practice of my invention, to the particular embodiment set forth.

40 What I claim is:

1. A raincoat consisting of a cape having shoulders, and a neck opening between said shoulders, said cape comprising a rear apron and a forward apron, and a skirt connected to the lower middle portion of the rear apron at the upper rear portion of said skirt, said skirt having a flap on each side extending around to the front side of the raincoat, said flaps each having an upper edge 45 at each side below each shoulder whereby an arm hole is formed at each side of the raincoat between each of said edges and its corresponding shoulder, and connecting means extending upwardly from the upper 50 and forward portion of each of said flaps at the front of said raincoat and connected to the inner side of the forward apron at an elevated point so as to form spaces covered by said forward apron and lying in front 55 of said connecting means, to receive the arms.

2. A raincoat consisting of a cape having shoulders and a neck opening between said shoulders, and having a forward apron, and 60 a skirt having an upper edge at each side

near the lower edge of said cape, and cooperating with said cape to form an arm-hole at each side of the raincoat between each of said edges and its corresponding shoulder, said skirt having extensions at the 70 front projecting upwardly and attached to the inner side of said apron at an elevated point so as to form spaces behind said forward apron and in front of said extensions to receive the arms. 75

3. A blank for forming a raincoat consisting of an upper portion to form a cape, having a central gap to form a neck opening, and having diverging edges extending outwardly from said gap to form meeting edges 80 for the forward side of the cape, said upper portion also having side edges extending up to meet said diverging edges, and a lower portion of substantially rectangular form having a flap extending toward one side and 85 another flap extending toward the other side, said flaps each having an upwardly extending connecting flap to be attached to the said upper portion.

4. A blank for forming a raincoat, consisting of an upper piece to form a cape, having a central gap to form a neck opening, and having diverging edges extending outwardly from said gap to form meeting edges for the forward side of the cape, said 90 upper piece also having side edges extending up to meet said diverging edges, and a separate lower piece of substantially rectangular form attached near its upper edge to the middle lower portion of the said upper piece, and having a flap extending toward each side, each of said flaps having a separate piece attached thereto and extending upwardly from its upper edge to be attached to the said upper piece. 95

5. A blank for forming a raincoat consisting of an upper portion to form a cape, having a central gap to form a neck opening, and having diverging edges extending outwardly from said gap to form meeting 100 edges for the forward side of the cape, said upper portion also having side edges extending up to meet said diverging edges, and a lower portion of substantially rectangular form, having a flap extending toward each 105 side, said flaps each having an upwardly extending connecting flap to be attached to the said upper portion, a cord extending along the edge of said blank, and a hem formed on the edge of said blank enveloping said 110 cord.

6. A raincoat formed of frangible material consisting of a cape having shoulders, and a neck opening between said shoulders, and having a forward apron, and a skirt 115 having an upper edge below each shoulder and near the lower edge of said apron whereby an arm hole is formed at each side of the raincoat between each of said edges and its corresponding shoulder, said skirt 120 125

130

4
having extensions of the frangible material
at the front projecting upwardly and at-
tached to the inner side of said apron at an
elevated point so as to form spaces behind
5 said forward apron to receive the arms, said
extensions having substantially vertical
edges, and having cords extending upwardly

along the said edges, and hems formed at the
said edges enveloping said cords.

Signed at New York in the county of New York
and State of New York this 20th day
of December A. D. 1916.

FRANK W. HOWARD.
